SPINNING AND LIKE TEXTILE FRAME

Oswald Lambert, Tamise, Belgium

Application November 12, 1937, Serial No. 174,244
In Great Britain November 19, 1936

3 Claims. (Cl. 118—47)

This invention relates to the driving of the spindles of spinning, twisting and like textile frames for jute, flex, hemp, cotton and other fibres, and is particularly applicable to the driving of ring spinning and twisting frames.

According to the invention, for driving the spindles of such frames there is employed at least one endless flexible belt or rope of any desired section, hereinafter referred to for convenience as a rope, which is looped in a vertical plane, at one side only of a row of spindles, and the upper flight of which is pressed into driving engagement with the wharves of the spindles by means of loaded jockey rollers, while the lower flight is passed around a tensioning pulley located between ends of the row of spindles.

The rope may be arranged to circulate around two pulleys disposed at opposite ends of the frame, one of said pulleys being the driving pulley and a drive being taken through speed reducing gearing from the other pulley to the drawing roller shaft of the frame, provision being made in the gear train for exchange of pinions to permit variation of the speed of rotation of the drawing roller shaft.

The invention is illustrated in the accompanying drawings in which Fig. 1 is a front elevation and Fig. 1^a a plan showing a spindle driving belt and belt-tensioning means of a spinning frame. Figs. 2 and 3 are elevations at right angles to one another showing a jockey roller arrangement for the belt. Figs. 4 and 5 are elevations at right angles to one another showing reduction gearing for transmitting power from the belt to the drawing roller shaft of the frame. Figs. 6 and 7 are elevations at right angles to one another showing a modified jockey roller arrangement. Fig. 8 is an elevation and Fig. 9 a plan showing a further jockey roller arrangement.

Referring to Figs. 1 and 1^a, a row of bobbin spindles 1 of which only a few are shown are driven by an endless rope 2 of which the upper flight is engageable with the wharves 3 of the spindles. The rope is trained around a pulley 5 at one end of the frame and around a driving pulley 6 at the other end of the frame, and its lower or "slack" flight is looped around an inclined fixed guide pulley 7 and a pulley 8 which is pulled in rope-tensioning direction by a weight 10 connected thereto by a rope 11.

As shown in Figs. 2 and 3, the rope 2 is pressed into driving engagement with each wharve 3 by means of a jockey roller 4 carried by a yoke lever 12 depending from a pivot 13 and influenced by tension springs 14 in the direction to cause the

roller 4 to maintain the rope 2 in driving engagement with the respective wharve 3. The pivot 13 is carried by a bracket 15 located on the underside of the spindle rail 16 and embracing the spindle journal sleeve 17. An adjustable stop screw 18 on the lever 12 is engageable with a stop 19 on the bracket 15 whereby to limit the movement of the roller 4 in rope-pressing direction.

As shown in Figs. 4 and 5, the pulley 5 constitutes a driver for a worm and worm-wheel speed reduction gear unit 20 which transmits power to the drawing roller shaft 21 of the frame. A sprocket 22 on the output shaft of the reduction gear is wrapped by a chain 23 which also wraps a sprocket 24 which is unitary with a spur wheel 25 meshing with a pinion 26 on the drawing roller shaft 21. The sprocket 24 and its spur wheel 25 are journaled on a stud on the upper end of an arm 27 which is angularly adjustable about the axis of the sprocket 22, the arrangement being such that the speed of rotation of the shaft 21 may be varied as required by the adoption at 25 and 26 of spur wheels with the requisite numbers of teeth.

Figs. 6 and 7 show a modified form of jockey roller arrangement in which the jockey roller 4 is mounted on the upper arm 29 of a two-armed pedal lever fulcrumed at 30 and presenting at the lower end of its lower arm 31 a pedal 32. The roller 4 presses on the rope 2 under the action of a weight 33 attached to a cord 34 trained over a pulley 35 and connected, through the medium of a tension spring 38, with a twin-link 36 pivotally connected at 37 at its forward end to the arm 29. As will be understood, by actuation of the pedal 32 the roller 4 may be disengaged from the rope 2 in opposition to the action of the weight 33, so as to interrupt the drive to the respective spindle 1. When the pedal 32 is actuated, a brake member 38^a is moved into engagement with the wharve 3 so as quickly to arrest rotation thereof.

Figs. 8 and 9 show a further jockey roller arrangement in which the jockey roller 4 is mounted on a slide 39 which is pulled in the direction to press the rope 2 against the wharve 3 by a weight 40 acting on the slide through the medium of a spring 41. For the purpose of temporarily holding the roller 4 clear of the rope 2 so as to interrupt the drive to the spindle, there is provided a double-armed manually operable lever 42, 43 which is pivoted on the slide 39 coaxially with the roller 4 and which is rockable from the position shown in full lines into the position shown in dotted lines in Fig. 9, whereby to hold the

roller 4 clear of the rope 2. The inner arm 42 of the lever 42, 43 presents a cam-shaped part 44 and a concave part 45 so contrived that, when the lever is rocked from the full line position into the dotted line position, the cam-shaped part 44 engages the hub 46 of the wharve whereby the roller 4 is forced in the direction away from the wharve, and, when the part 45 engages the hub 46, the lever sets itself in the dotted line position and holds the roller 4 in inoperative position, until rocked in the reverse direction so as to re-establish the drive to the spindle. As will be understood, the spindle will be braked by the engagement of the lever with the hub 46.

15 The tension spring 38 or 41 responds readily to vibrations set up by inequalities of the belt 2, so that these vibrations are not transmitted to the respective weights, and continuity of engagement of the jockey roller with the rope is ensured.

20 I claim:—

1. A spinning, twisting, or like textile frame comprising a series of spindles, wharves on said spindles, an endless travelling rope looped in a vertical plane at one side of said row of spindles, 25 a rope-driving pulley at one end of said row, a driven pulley at the opposite end of said row, said pulleys wrapped by said belt, a rope-tensioning pulley engaging the lower flight of said endless rope and located intermediate said driving and 30 driven pulleys, jockey rollers urged in the direction to press the upper flight of said endless rope into engagement with said wharves, a drawing roller shaft, and gearing connecting said driven pulley with said shaft.

35 2. A spinning, twisting, or like textile frame, comprising, in combination with a spindle rail, at least one row of spindles journalled in said rail,

wharves on said spindles below said rail, an endless travelling rope for driving said wharves, said endless rope looped in a vertical plane at one side only of said row of spindles, a pulley at one end of said row of spindles, a driven pulley at the opposite end of said row of spindles, said pulleys wrapped by said endless rope, jockey rollers for pressing the upper flight of said endless rope into engagement with said wharves, suspended weights for loading said jockey rollers, connections including springs between said weights and said jockey rollers, and a rope-tensioning pulley located between said first-mentioned pulleys and engaging the lower flight of said endless rope.

3. A spinning, twisting, or like textile frame, comprising, in combination with a spindle rail, at least one row of spindles journalled in said rail, wharves on said spindles below said rail, an endless travelling rope for driving said wharves, said endless rope looped in a vertical plane at one side only of said row of spindles, a pulley at one end of said row of spindles, a driven pulley at the opposite end of said row of spindles, said pulleys wrapped by said endless rope, jockey rollers for pressing the upper flight of said endless rope into engagement with said wharves, levers on which said jockey rollers are mounted, each of said levers operable manually to move the respective jockey roller in the direction away from the associated wharve, weights urging said jockey rollers in the 20 direction to press the upper flight of said endless rope against said wharves, connections including springs between said weights and said jockey rollers, and a rope-tensioning pulley located between said first-mentioned pulleys and wrapped by the lower flight of said endless rope.

O. LAMBERT.
